United States Patent Office

Des. 193,518
Patented Sept. 4, 1962

193,518

DESK

Charles U. Deaton, 9635 W. Colfax Ave.,
Lakewood, Colo.

Filed Dec. 18, 1959, Ser. No. 58,722

Term of patent 14 years

(Cl. D33—7)

FIG. 1

FIG. 2

FIG. 3

FIG. 4

FIG. 5

FIG. 1 is a perspective view of a desk embodying my new design;

FIG. 2 is a front elevational view thereof;

FIG. 3 is a left side elevational view thereof;

FIG. 4 is a right side elevational view thereof; and

FIG. 5 is a rear elevational view thereof.

I claim:

The ornamental design for a desk, substantially as shown.
